Primary Examiner — Brett Miller(74) *Attorney, Agent, or Firm* — Michael Best and Friedrich LLP(57) **CLAIM**

The ornamental design for a television receiver, as shown and described.

DESCRIPTION

FIG. 1 is a rear, top, left perspective view of a first embodiment of a television receiver showing our new design;

FIG. 2 is a rear elevational view thereof;

FIG. 3 is a left side elevational view thereof; and,
 FIG. 4 is a partially enlarged rear elevational view thereof along the lines 4-4 and 4'-4' of FIG. 2.

The even-dash broken lines illustrating portions of the television receiver form no part of the claimed design. The single dot-dash broken lines and the double dot-dash broken lines defining boundaries of the claimed design, wherein inside area of the single dot-dash broken lines is claimed excepting inside area of the double dot-dash broken lines. The single dash and double dash broken lines form no part of the claimed design.
